UNITED STATES PATENT OFFICE.

LABAN B. LAKE AND EDMUND SAWYER, OF TOLEDO, OHIO; SAID SAWYER
ASSIGNOR TO LEWIS M. CORY, OF SAME PLACE.

ADJUSTABLE HOLDER FOR BOOKS, &c.

SPECIFICATION forming part of Letters Patent No. 360,965, dated April 12, 1887.

Application filed April 14, 1886. Serial No. 193,876. (No model.)

To all whom it may concern:

Be it known that we, LABAN B. LAKE and EDMUND SAWYER, both citizens of the United States, residing at Toledo, in the county of Lucas and State of Ohio, have invented new and useful Improvements in Adjustable Holders for Books and Sheet-Music on Organs and Pianos, of which the following is a specification.

10 Our invention relates to improvements in devices for holding sheet-music and music-books in a desired position on the music-rack of a piano or organ, or on portable racks for music when playing with any other instrument; and the objects of our improvements are to provide a cheap, simple, and durable device for the purpose that may be built on the music-racks when the instruments are constructed, or a device made so as to be easily 15 attached to or detached from the music-rack of any instrument, and at the same time adjustable, so as to adapt its use to any sized book desired. These objects we attain in the manner herein after specified, and shown in the drawings illustrating the device hereto annexed, in which—

Figure 1 is a face view of a rack with the device built upon it. Fig. 2 is an edge view from the top of the same, showing the device 30 holding a book in the proper position. Fig. 3 is an end view of the same. Figs. 4 and 5 are edge and end views of the holder, as constructed separate and made attachable to and detachable from any music-rack of a piano or organ. Figs. 6 and 9 are enlarged details of 35 parts that slide and turn. Figs. 7 and 8 are views of a modified form of the device, showing a dovetailed block sliding in a groove.

A represents an ordinary piano or organ 40 music-board, made either of slats or in fret-work, to the face of which is attached a raised slat, C, having the edges cut under in the form of a tenon of a dovetail joint. E is a sliding clamp-plate on the raised slat C, to which is 45 pivoted a spring-clamp, H, that may be swung around in any direction desired on the pivot.

B is the ordinary base-ledge, upon which the book D rests.

Figs. 1, 2, and 3 show the different views of 50 the device as built on the rack.

In Figs. 4, 5, 6, and 9 we represent the different views of our device when it is made attachable or detachable to the music-board of any organ or piano in which a piece having two sections, C and C², is worked out and finished like a piece of molding, the edges of which have a double bevel to receive the adjustable sliding clamps E and L. The sliding clamp-plate E has pivoted to it at the spring-clamp H, which may be turned, as desired, to 55 replace or adjust the book. The sliding clamp-plate L has a shorter spring clamp or arm, K, extending out from it, which is designed to pass through the openings in the ordinary music-racks on organs and pianos, and 60 clamp over some of the members of the same and to meet all demands, and adapted to be attached at any place. The clamp L may be 65 slid off at the end and reversed.

In cases where the folding of a piano or organ requires a more compact device, we design to use a modified form, (shown in Figs. 7 and 8,) in which, instead of the sliding clamp-plate E on the raised slat C, the bevel-edged block I slides in a dovetailed groove below the 70 face of the slat C², accomplishing substantially the same end and purpose. The slat on which the clamp slides will be provided at each end, as illustrated in Fig. 1, with a slot-pin, h, to 75 check the movement of the slide and protect it from passing entirely from off the slat.

The parts of this device we design to make of any suitable metal and finish in accordance with the class of work to which it is to be attached, cushioning with felt or baize those 80 parts which by use tend to mar the finish of the instrument. The length and other dimensions of the device and its parts we design to 85 make suitable for any sized book desired.

We are aware that it is old to provide spring-fingers that can be turned and adjusted to support books of different sizes. We are also aware that a music-holder has been constructed of a plain rectangular bar without grooves or incisions, with tubes entirely surrounding the 90 same and sliding thereon, said tubes being provided with springs for clamping the leaves of a book, and the bar having offsets at each end. Such, therefore, we do not claim.

Having thus described our invention so that 95

any one skilled in the arts can make and use the same, what we claim as new, and desire to secure by Letters Patent, is—

1. In a holder for sheet-music and books, the combination, with a slat, C, having beveled sides, and provided with stops h, of a slide, E, formed to fit the beveled sides of said slat, and a spring-finger, H, of elastic material, pivoted directly to the slide to turn thereon, substantially as described.

2. In a holder for sheet-music and books, the slat formed with the dovetailed sections C, the sliding clamp-plate E, provided with

spring-clamp H, and the sliding clamp-plate L, provided with spring-clamp K, the said clamp-plates being dovetailed to conform to the dovetails of the slat, substantially as described. 15

In testimony whereof we have hereunto set our hands in the presence of two subscribing witnesses. 20

LABAN B. LAKE.
EDMUND SAWYER.
